UNITED STATES PATENT OFFICE.

CHARLES EDWARD LUCKE, OF NEW YORK, N. Y., ASSIGNOR, BY DIRECT AND MESNE ASSIGNMENTS, OF ONE-THIRD TO LOUIS WILPUTTE AND TWO-THIRDS TO ALICE A. WILPUTTE, BOTH OF NEW ROCHELLE, NEW YORK.

COKE-OVEN AND METHOD OF OPERATING SAME.

1,332,909.

Specification of Letters Patent.

Patented Mar. 9, 1920.

Application filed March 4, 1918. Serial No. 220,387.

To all whom it may concern:

Be it known that I, CHARLES EDWARD LUCKE, a citizen of the United States of America, residing in the city, county, and State of New York, have invented certain new and useful Improvements in Coke-Ovens and Methods of Operating Same, of which the following is a true and exact description, reference being had to the accompanying drawings, which form a part thereof.

My present invention relates to regenerative coke ovens, and particularly to by-product coke ovens of the well known type in which the oven structure comprises horizontally elongated coking retorts separated by heating walls, each of which is formed with vertical heating flues or combustion chambers extending in a row from one end of a heating wall to the other, and with a horizontal passage or channel connecting the upper ends of the vertical flues. The flues in each heating wall are divided into two groups lying at opposite sides of a transversal plane located approximately midway between the ends of the heating wall. The two groups of flues are alternately supplied at their lower ends with preheated air and fuel gas, which may or may not be preheated. Combustion occurs in the vertical flues which at any one instant are being supplied with air and fuel gas, and the products of combustion pass out of the upper ends of these flues into the upper horizontal passage, flowing through the latter to and into the upper ends of the flues of the other group, and passing from the lower ends of the latter into the regenerator or regenerators connected to those flues. At intervals the flow through the two groups of vertical flues is reversed. The operation of a coke oven having this type of the system in its heating walls, as heretofore constructed, is characterized by a tendency to unequal distribution of flow among the different vertical flues, and particularly by a tendency to a flow distribution among the flues of each group which is different when the flow is one direction through those flues from what it is when the flow through those flues is in the opposite direction. This tendency toward a faulty distribution results from the changes in velocity head and consequent

changes in static pressure in the upper horizontal passage connecting the tops of the vertical flues, and in the horizontal passages through which the lower ends of the flues are connected to the regenerators, or through which the air, or air and gas to be preheated, is supplied to the regenerators, and the waste products of combustion are withdrawn from the regenerators.

The general object of my invention is to improve coke ovens having the kind of heating wall referred to, by so arranging the horizontal passages connected directly, or through the regenerator, to the lower ends of the vertical flues, that the pressure differential at the opposite ends of any vertical flue will be practically the same as the pressure differential between the opposite ends of any other flue in the same group with either direction of flow through that group of flues. I accomplish this by arranging the supply and outlet channels connected to the lower ends of the vertical flues, either directly or through the regenerators, in such manner that there will be variations in static pressure, resulting from changes in velocity head, impressed on the lower ends of the vertical flues of each group corresponding, and approximately equal to the changes in static pressure occurring in the portion of the upper horizontal channel of the heating wall to which the upper ends of the flues of that group are connected.

The various features of novelty which characterize my invention are pointed out with particularity in the claims annexed to and forming a part of this specification. For a better understanding of the nature and object of my invention, and the problem which it has been devised to overcome, reference should be had to the accompanying drawings and descriptive matter in which I have illustrated and described some of the various forms in which my invention may be advantageously embodied and carried out.

Of the drawings:

Figure 1 is a diagrammatic sectional elevation of a portion of a coke oven structure, the section being taken on the line 1—1 of Fig. 2.

Fig. 2 is a sectional plan taken on the line 2—2 of Fig. 1.

Fig. 3 is a pressure diagram illustrating static pressure conditions in the apparatus shown in Figs. 1 and 2.

Fig. 4 is a similar pressure diagram illustrating pressure conditions existing in prior ovens having the heating wall flue arrangement illustrated in Fig. 1.

Fig. 5 is a sectional elevation of a coke oven having longitudinal regenerators, the 10 section being taken on the broken line 5—5 of Fig. 6.

Fig. 6 is a partial sectional plan, the section being taken on the line 6—6 of Fig. 5.

Fig. 7 is a transverse section taken partly 15 on the line 7^A—7^A of Fig. 5, and partly on the line 7^B—7^B of Fig. 5.

Fig. 8 is a sectional elevation of a coke oven having cross regenerators, the section being taken on the line 8—8 of Fig. 10.

Fig. 9 is a partial sectional plan, the section being taken on the lines 9—9 of Figs. 8 and 10.

Fig. 10 is a sectional elevation taken partly on the line 10^A—10^A and partly on the 25 line 10^B—10^B of Fig. 8.

Fig. 11 is a sectional elevation of a coke oven in which the various vertical heating flues in each heating wall are connected each to a different regenerator from that to which 30 the other of these flues is connected, the section being taken on the line 11—11 of Fig. 13.

Fig. 12 is a sectional plan taken on the line 12—12 of Figs. 11 and 13, and

Fig. 13 is a sectional elevation taken 35 transversely to Fig. 11 partly on the line 13^A—13^A and partly on the line 13^B—13^B of Fig. 11.

In the drawings, and referring first to 40 the coke oven arrangement shown somewhat diagrammatically in Figs. 1 and 2, C represents a heating wall formed with a row of vertical combustion flues extending from one end of the heating wall to the other, and 45 all connected at their upper ends by the upper horizontal passage B. For convenience, the group of vertical flues at the left hand side of the heating wall in which the flow at any one instant is always in the same direction, are designated by the symbol A, and the flues of the other group are designated by the symbol a. Associated with the flues A and a are a co-operating pair of sole channels D and d, which extend longitudinally of 50 the heating wall from the opposite ends of the latter past the flow reversal plane indicated in Figs. 1 and 2 by the line X X. The group of flues A all lie at one side, and the flues a all lie at the other side of this plane. 55 The flow reversal plane X X is shown as located midway between the ends of the heating wall, though it is common practice, where the coking chambers taper in width from one end to the other, to displace the 60 flow reversal plane slightly from the mid-

dle of the heating wall, putting more flues in the groups at the sides of the thin ends of the coking chambers than in the groups alongside the thicker ends of the coking chambers.

70

The lower ends of the flues A are separately connected by ports E to the sole channel D, and the lower ends of the flues a are separately connected by ports e to the sole channel d. The sole channels D and d are provided with regenerator connections D' and d' respectively, the regenerators not being shown in these figures.

75

The distinguishing characteristic of the embodiment of my invention somewhat diagrammatically illustrated in Figs. 1 and 2 is found in the fact that the two sole channels D and d overlap at their inner ends and each has its regenerator connection at the opposite side of the flow reversal plane from that at which the sole channel is connected by the ports E or e, as the case may be, to the corresponding group of flues A or a. In consequence of this novel arrangement of the sole channels, the flow through each of 80 the sole channels B and b is always opposite in direction to the longitudinal flow through the portion of the upper horizontal channel directly connected to that sole channel by the corresponding group of vertical 85 flues A or a. The advantage obtained by this is most easily explained by reference to Figs. 3 and 4.

85

In Fig. 3 the lines 1^A to 8^A, inclusive, represent the center lines of the flues A in the order in which these flues run from the left end of the heating wall to the flow reversal plane, and the lines 1^a to 8^a, inclusive, represent the center lines of the group of flues a in the order in which these flues extend from 100 the right hand end of the heating wall toward the flow reversal plane. The line P represents a certain base static pressure. The line P B represents the static pressure in the upper horizontal passage B at different points along the length of the latter. The line P D represents the static pressure in the sole channel D, and the line P d represents the static pressure in the sole channel d when the direction of flow is that indicated 105 in Fig. 1 by the arrows applied to that figure. By reference to the line P B it will be seen that the static pressure in the upper horizontal passage is higher at each end than at the center of the passage. This is a consequence of that law of flow known as Bernouilli's theorem, which is that, disregarding friction, the total pressure in a passage through which fluid flows is the same at every point along the path of flow 110 and at each point is equal to the sum of the static pressure and the velocity head of dynamic pressure, at that point. The velocity of flow in the upper horizontal passage is a maximum at the flow reversal plane 115 and at each point is equal to the sum of the static pressure and the velocity head of dynamic pressure, at that point. The velocity of flow in the upper horizontal passage is a maximum at the flow reversal plane 120 and at each point is equal to the sum of the static pressure and the velocity head of dynamic pressure, at that point. The velocity of flow in the upper horizontal passage is a maximum at the flow reversal plane 125 and at each point is equal to the sum of the static pressure and the velocity head of dynamic pressure, at that point. The velocity of flow in the upper horizontal passage is a maximum at the flow reversal plane 130

X X and decreases progressively to the ends of the passage where it becomes zero, since all of the fluid passing into the upper horizontal passage through one group of flues, 5 and out through the other group of flues, passes across the flow reversal plane, while the volume of flow through the horizontal passage at any point at either side of this plane is decreased by the amount of the 10 flow through the intervening vertical flues. At the flow reversal plane, the velocity head is a maximum and the static pressure a minimum, while at the ends of the horizontal passage the velocity head is zero and the 15 static pressure is a maximum.

The static pressure in the sole channel *d* will be constant in the portion of the sole channel between the regenerator connection *d'* and the flow reversal plane **X X**, and will 20 increase as the velocity head decreases from the flow reversal plane to the outer end of the sole channel. Similarly, the static pressure in the sole channel *D* will be constant in the portion of this sole channel between 25 the flow reversal plane **X X** and the regenerator connection *D'* and will rise progressively from the flow reversal plane to the opposite end of the heating wall. The pressure differential at the opposite ends of each 30 vertical flue *A* is indicated by the length of the portion *Y* of the corresponding line 1^a to 8^a , inclusive, cut off between the curves *P d* and *P B*, and similarly the pressure differential between the opposite ends of each 35 of the flues *A* is indicated by the lengths of the portion *y* of the corresponding line 1^a to 8^a cut off between the curves *P B* and *P D*. The flow through each of the combustion flues is a direct function of the pressure 40 differential at the opposite ends of the flue. It follows, therefore, that the variations in static pressure in the sole channels *D* and *d* tend toward an equal distribution of flow among the flues *a* and *A*. It is apparent 45 moreover that this tendency toward equal flow distribution is maintained when the flow through the flues and horizontal passages is reversed. In general, with this arrangement, if it is found desirable to modify 50 the flue distribution as by the use of slide brick or dampers at the upper ends of the vertical flues, as for example to increase the amount of flow through the flues adjacent the ends of the heating wall in order to compensate for increased radiation, this adjustment 55 will be operative to modify the flow among the flues of each group in the same way with either direction of flow through that group of flues. Similarly, if it is desired 60 to progressively increase the flow from one end of the heating wall to the other to compensate for the varying thickness of the coal charge being coked when the coking chamber varies in thickness from one end to 65 the other, the slide brick may be employed

to progressively throttle the various vertical flues *A* and *a* in progressively increasing amounts from one end of the heating wall to the other, and the effect of this throttling will be to vary the flow through the flues 70 similarly with either direction of flow.

The practical importance of my invention in the form illustrated in Figs. 1 and 2 is strikingly apparent when the pressure diagram shown in Fig. 3 is compared with the 75 pressure diagram shown in Fig. 4. The last mentioned diagram represents pressure conditions in an oven having a flue system of the kind shown in Fig. 1, but with sole channels in which the longitudinal flow is at any 80 instant in the same direction as in the portion of the upper horizontal channel to which the sole channel is connected by the corresponding group of vertical flues. This is the case, for instance, with the well known type of 85 oven construction shown by the U. S. patent to Hoffman 492,400 and the U. S. patent to Koppers 738,918. The static pressure in the upper horizontal passage of such an oven decreases from the ends of that passage to 90 the flow reversal plane, as indicated in Fig. 4 by the line *P B X*, *P X* representing a base pressure line. The static pressures in the sole channels increase in this case, however, from the outer ends of the sole channels 95 toward the flow reversal plane. In Fig. 4 the pressure in the sole channel serving, at the instant, as the supply channel is indicated by the line *P d x*, and the static pressure in the sole channel serving as the waste 100 heat outlet channel at that instant is indicated by the line *P D X*. It is apparent that the static pressure differentials at the opposite ends of the vertical flues increase 105 from the outer end of the heating wall toward the flow reversal plane in the "on" flues, and increase from the flow reversal plane to the opposite end of the heating wall in the case of the "off" flues. This tends to concentrate up flow in the flues 110 adjacent the flow reversal plane, and to concentrate down now in the flues remote from the flow reversal plane. This is obviously true with either direction of flow and cannot be adequately corrected by slide brick or 115 damper regulation of the different vertical flues, for if the slide bricks or dampers be so adjusted with respect to one group of flues as to equalize the up flow through these flues, that is by throttling the flues progressively from the outer end of the heating wall toward the flow reversal plane, this throttling augments the concentration of flow 120 among the flues adjacent the end of the heating wall when the flow is reversed.

In Figs. 5, 6 and 7 I have illustrated the application of the form of my invention somewhat schematically illustrated in Figs. 1 and 2, to a coke oven of a general design now extensively and successfully used in 130

practice in Europe. In Figs. 5, 6 and 7 each heating wall C¹⁰ is formed with a series of vertical flues A¹⁰ and a¹⁰ extending from one end of the heating wall to the other, 5 and all connected at their upper ends by a common horizontal passage B¹⁰. Below the vertical flues are arranged sole channels D¹⁰ and d¹⁰, which in this case extend from one end of the heating wall to the other. 10 The sole channels D¹⁰ are connected to a regenerator G running longitudinally of the oven battery, that is transversely of the heating walls by connections D¹¹. Similarly, the sole channels d¹⁰ are connected 15 through the connecting channels d¹¹ to a longitudinally running regenerator g at the opposite side of the battery from the regenerator G. For structural reasons the sole channels d¹⁰ are arranged in pairs, one 20 pair of these channels being located between every other pair of adjacent heating walls. Each sole channel d¹⁰ is connected to the flues a¹⁰ in the immediately adjacent heating wall. Similarly, the sole channels D¹⁰ 25 are arranged in pairs, one pair between every other pair of heating walls, and the two channels D¹⁰ of each pair are connected to the corresponding groups of flues A¹⁰ in the two adjacent heating walls. With 30 this arrangement the flues A¹⁰ of any one heating wall are connected to a sole channel D¹⁰ lying at one side of the central plane of the heating wall as seen in Fig. 7, while the flues a¹⁰ of the same heating wall are 35 connected to a sole channel d¹⁰ lying at the opposite side of the longitudinal central plane through the heating wall. In the construction illustrated in Figs. 5, 6 and 7 the connecting passage between each flue A¹⁰ 40 and the sole channels D¹⁰ comprises a vertical portion E¹¹ and a lateral portion E¹², and similarly the connections between the flues a¹⁰ and the sole channels d¹⁰ each comprises a vertical portion e¹¹ and a lateral portion e¹². 45 Gas passages H opening into the bottoms of the flues A¹⁰ and a¹⁰ supply combustible gas to these flues when combustion is to take place therein.

50 It will be understood that gas is supplied through the corresponding passages H to the lower ends of all flues A¹⁰ in one stage of operation. In the same stage of operation air passes into the regenerator G as 55 through the supply passages I, is heated in the regenerator G, and passes from the latter through the connections D¹¹, sole channels D¹⁰ and ports E¹⁰ and E¹¹ to the lower ends of the flues A¹⁰. At the same 60 time products of combustion pass out of the flues a¹⁰ through the ports e¹⁰ and e¹¹ to the sole channels d¹⁰, and from the latter, pass through the connections d¹¹ into the regenerator g, and eventually passes out of the 65 latter into the off heat tunnel j. When the

flow is reversed air passes into the regenerator g through the air inlets i, and the heated air passes out of the regenerator g through the regenerator connections d¹¹ into the sole channels d¹⁰, and passes thence through the 70 ports e¹⁰ and e¹¹ into the flues a¹⁰, which in this stage also receives combustible gas through the corresponding gas supply passages H. In this stage of operation the 75 products of combustion pass out of the lower ends of the flues A¹⁰ into the sole channels D¹⁰, and from the latter pass through the regenerator connections D¹¹ into the regenerator G and eventually pass out of the bottom of that regenerator into the 80 waste heat tunnel J.

In Figs. 8, 9 and 10 I have illustrated the application of my invention to a coke oven having a pair of so-called cross regenerators G¹⁵ and g¹⁵ placed end to end between each 85 adjacent pair of pillar walls I, which are parallel to and beneath the heating walls. The regenerators G¹⁵ are separated from the regenerators g¹⁵ at or adjacent the center line of the battery by a division wall G¹⁷. 90 In this form of my invention there are a pair of sole channels D¹⁵ and d¹⁵ located between each pair of pillar walls above the regenerators, and each extending from one side edge of the battery to the other. 95 Each sole channel D¹⁵ is connected by ports D¹⁶ in its bottom wall to the corresponding regenerator G¹⁵ beneath it, and is also connected by a series of ports E¹⁵ to the group of flues A¹⁵ in an adjacent heating wall. 100 Similarly, the sole channel d¹⁵ is connected by ports d¹⁶ to the regenerator g¹⁵ over which it extends, and is connected by ports e¹⁵ to the lower ends of the vertical flues a¹⁵ in an adjacent heating wall. The regenerators g¹⁵ and the ports E¹⁵ and d¹⁶ 105 are all on one side of the flow reversal plane, while the regenerators G¹⁵ and the ports e¹⁵ and d¹⁶ are on the opposite side of the flow reversal plane. It is to be noted that for 110 structural reasons the sole channels D¹⁵ and d¹⁵, connected to the vertical flues A¹⁵ and a¹⁵ in the same heating wall, lie on opposite sides of the pillar wall I beneath that heating wall. H¹⁵ represents the gas supply connections to the lower ends of the vertical flues. Air to be preheated and products of combustion are alternately admitted to, and discharged from the regenerators G¹⁵ and g¹⁵ through the corresponding ports G¹⁶ 115 and g¹⁶. The general mode of operation of the oven shown in Figs. 8, 9 and 10 is essentially the same as that of the oven shown in Figs. 5, 6 and 7.

In Figs. 11, 12 and 13 I have illustrated 125 the application of my invention to a coke oven in which the various flues A²⁰, at one side of the flow reversal plane, are connected by ports E²⁰ to separate regenerators G²⁰ beneath them, while the vertical flues a²⁰ at 130

the other side of the flow reversal plane, are connected by ports e^{20} to separate regenerators g^{20} located beneath the flues a^{20} . As shown, the regenerative spaces G^{20} or g^{20} beneath the vertical flues A^{20} or a^{20} in each row running transversely to the retorts and heating walls are connected by equalizing ports G^{21} or g^{21} in which checker brick may, or may not be piled.

10 Beneath the regenerators are located sole channels D^{20} and d^{20} , which run parallel to the heating walls from one side edge of the battery to the other. The sole channels D^{20} are connected by ports K^{20} to the regenerative spaces G^{20} and the sole channels d^{20} are connected by ports k^{20} to the regenerative spaces g^{20} above them. The ends of the sole channels D^{20} at the same side of the flow reversal plane as the regenerators G^{20} are closed at D^{21} , while the opposite ends of these sole channels are alternately connected (by means not shown) to a waste heat conduit and to the atmosphere or other source of air to be preheated. Similarly, the sole channels d^{20} have their ends at the side of the flow reversal plane at which the regenerator chamber g^{20} are located closed at d^{21} , while their opposite ends are alternately connected to a waste heat conduit and to the atmosphere or other source of air to be preheated. Combustible gas is supplied to the vertical flues through the passages H . The operation of this form of my invention will be understood without further explanation.

15 It is to be noted that the construction shown in Figs. 11, 12 and 13 possesses the especial advantage that the relatively low temperatures to which the sole channels D^{20} and d^{20} are exposed minimize the liability to objectionable leakage through the walls of these sole channels.

While in accordance with the provisions of the statutes I have illustrated and described the best form of my invention now known to me, it will be apparent to those skilled in the art that changes may be made in the form of my invention without departing from its spirit, and that some features of my invention may sometimes be used to advantage without a corresponding use of other features of the invention.

Having now described my invention, what I claim as new and desire to secure by Letters Patent, is:

1. The method of supplying air to and withdrawing waste products of combustion from the vertical flues of a regenerative coke oven of the type in which each heating wall

is formed with a plurality of vertical flues all of which are connected at their upper ends by a common horizontal passage, and in which the lower ends of such of said flues in each heating wall as lie at one side of the flow reversal plane are separately connected to one horizontal channel, while the remaining vertical flues in the heating wall are separately connected at their lower ends to a second horizontal channel, which consists in alternately supplying air to and withdrawing waste gas from each of said channels at the opposite side of the flow reversal plane from that at which the said channel is connected to the vertical flues.

2. A regenerative coke oven comprising coking retorts and heating walls, each of the latter being formed with two groups of vertical heating flues arranged at opposite sides of a flow reversal plane and with an upper horizontal channel to which the upper ends of the flues of both groups are connected, and means for alternately supplying pre-heated air to, and withdrawing products of combustion from the lower ends of the vertical flues comprising a pair of sole channels for each heating wall, one of which is separately connected to the lower ends of the vertical flues of one group and the other of which is separately connected to the lower ends of the flues of the other group in said wall, and each of which has an air inlet and waste gas outlet connection at the opposite side of the flow reversal plane from its connections to the corresponding group of flues.

3. A regenerative coke oven comprising coking retorts and heating walls, each of the latter being formed with two groups of vertical heating flues arranged at opposite sides of a flow reversal plane and with an upper horizontal channel to which the upper ends of the flues of both groups are connected, and means for alternately supplying pre-heated air to, and withdrawing products of combustion from the lower ends of the vertical flues comprising a pair of sole channels for each heating wall, one of which is separately connected to the lower ends of the vertical flues of one group and the other of which is separately connected to the lower ends of the flues of the other group in said wall, and each of which overlaps the other at the flow reversal plane and receives air and discharges products of combustion at the opposite of said plane from its connections to the vertical flues.

CHARLES EDWARD LUCKE.
